Henry G. Thompson, of New York, N. Y.
Assign to
The Hartford Carpet Company,
Letters Patent No. 1684, Dated Dec 9th 1862

The schedule referred to in these Letters Patent and making part of the same.

To all whom it may concern

Be it known that I, Henry G. Thompson, of the City, County, and State of New York, have invented or produced a new and original Design for a Pattern to be wrought into Tapestry, Ingrain, and other carpeting, in colors similar to those painted on the drawings accompanying this specification, or in other colors substituted in the place of those painted on the drawings herewith; and I do hereby declare that the drawings accompanying this specification, do give and convey to any one skilled in the
